(57) **CLAIM**

The ornamental design for a side cover for process cartridge for image forming device, as shown and described.

DESCRIPTION

FIG. 1 is a front view of a side cover for process cartridge for image forming device showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a front perspective view thereof; and,

FIG. 8 is a rear perspective view thereof.

The broken lines illustrate portions of the side cover for process cartridge for an image forming device that form no part of the claimed design.

1 Claim, 6 Drawing Sheets
